UNITED STATES PATENT OFFICE

2,403,184

ELECTRIC DISCHARGE LAMP

Eugene Lemmers, Cleveland Heights, Ohio, assignor to General Electric Company, a corporation of New York

Application December 26, 1942, Serial No. 470,119

3 Claims. (Cl. 176—122)

1

My invention relates to gaseous electric discharge devices and more particularly to discharge lamps of the cathode glow type. An object of my invention is to provide a lamp of this type which starts readily at low voltages and at the same time has a good light output. A feature of the invention is an arrangement of the cathode and anode such that they are closely spaced for easy starting, yet the discharge gap therebetween is substantially longer than the said spacing so that the lamp will have a good light output, this being accomplished without making either of the electrodes movable. Further features and objects of my invention will appear from the following description of a species thereof and from the drawing:

The single figure of the drawing is a perspective view of one species of lamp comprising my invention, together with a circuit therefor.

In one of its specific forms, the present invention may be considered as a modification of the type of lamp shown in application Serial No. 387,002, G. E. Inman et al., filed April 5, 1941, now Patent No. 2,341,990, dated February 15, 1944. The lamp shown in that application operates satisfactorily and with good efficiency from a source of current supply having a potential of about 24 volts. Lamps made in accordance with the present invention are capable of starting and operating on an approximately 12 volt circuit.

I have found that in a lamp of the type disclosed in the above-mentioned application if the anode is moved closer to the cathode, in general the light output slowly diminishes until at a spacing of the anode about two millimeters from the point on the cathode at which the cathode spot occurs, about ten per cent of the light output is lost. Up to this point very little change occurs in the arc volts or ability to start. However, as the anode is moved closer to the cathode, the discharge voltage may drop about ten per cent and the ability to start improves considerably. However, about forty percent more of the light output is lost when the anode is moved closer than about 2 millimeters to the cathode spot.

I have found that by placing the anode within one millimeter of the coiled cathode, and three to five millimeters from that part of the cathode where the spot forms, I am able to retain all the starting advantages of the closer spaced anode without the loss of light output. Such lamps start readily on 12 volt circuits and have arc voltages of from 6.25 to 8.5 volts.

Referring to the drawing, the particular form of lamp shown therein comprises a sealed glass

2

envelope 10 containing a suitable ionizable medium. The envelope may contain a fluorescent material as disclosed in the Inman et al. application referred to above, and, it may be made of a vitreous material which is transparent to ultraviolet rays where such radiation is to be utilized externally of the envelope. The ionizable medium may consist of a rare gas or a vaporizable material or mixtures thereof. I prefer to employ a mixture of argon and a small amount of mercury, the argon being at a pressure of, for example, .5 to 8 millimeters Hg, preferably a pressure of 3.5 to 4.5 millimeters.

The envelope contains a cathode 11 and an anode 12, the cathode 11 being mounted on lead-in conductors 13 and 14, and the anode being mounted on a lead-in conductor 15. The conductors 13, 14, and 15 extend through a conventional stem 16.

20 The cathode 11 is preferably a triple coil of the type disclosed and claimed in Patent No. 2,306,925, J. O. Aicher, dated December 29, 1942, and is coated with an electron-emissive material, preferably an alkaline earth oxide, or mixtures thereof, such as barium and strontium oxides. For the specific lamp shown in the drawing, which may be rated at about 3 watts, the cathode 11 may be made to the following specifications. The cathode wire may be tungsten having a diameter of .35 to .45 mil. This wire is wound at 400 turns per inch on a double mandrel (as disclosed in the Aicher patent) of 2 mil tungsten and 2.5 mil molybdenum. This primary coil is then coiled on a 6 mil molybdenum mandrel at 115 turns per inch. This secondary coil is then coiled on a 20 mil molybdenum mandrel at 44 turns per inch. This results in twelve triple turns with 4.5 to 5 millimeter spacing between turns. Obviously, there is an appreciable resistance and voltage drop between spaced points on the cathode coil.

25 The anode 12 is preferably made of a thin ribbon of nickel or molybdenum which, for the specific lamp referred to above, may be 4 millimeters wide, 5 mil thick and 25 millimeters long. As shown in the drawing, the anode 12 may be made substantially U-shaped, the bent portion having a diameter of about 3 millimeters, so that the distance between the outer surface of the 30 coiled cathode 11 and the inner surface of the anode 12 is less than 2 millimeters and preferably about 1 millimeter. Instead of making the anode 12 U-shaped, it may be made in the form of a cylinder. On the other hand, it may also be 35 made in the form of a wire which may be merely

an extension of the lead-in conductor 15, although I prefer the ribbon form wherein the ribbon curves about the cathode and has a surface of at least 16 square millimeters facing the cathode.

I prefer to activate the cathode 11 according to a special schedule. Thus the coil may be coated with an emissive mixture consisting of a mixture of carbonates of alkali earth metals suspended in a suitable binder, such as nitrocellulose. After the electrodes have been assembled in the envelope 10, the lamp is subjected to an exhaust schedule wherein the cathode is not activated, but is outgassed at a temperature of less than 1100° C. but above the temperature at which the carbonates will decompose. The preferred temperature is about 1050° C. The heating is done by connecting the cathode 11 across a suitable source of current. The correct temperature is obtained with a cathode having the proportions referred to above when the cathode is connected across a source of supply at 60 volts in series with a standard 60-watt 120-volt incandescent lamp. This heating is continued until no more CO₂ comes off. The lamp is then subjected to a seasoning schedule wherein the cathode is heated, by passing current therethrough, to about 1300° C. for from two to six minutes to season the lamp and bring the arc volts and starting volts within the proper limits, which in this case are a maximum arc voltage of 9 and a starting voltage of 12.

As shown in the drawing, the lead 13 is connected to the negative terminal 17 of a suitable source of current supply which may be a 12-volt storage battery. The lead 15 to the anode 12 is connected through a ballast resistance 18 to the positive terminal 19. The lead 14 is connected to the switch 20 so that, during starting, the cathode 11 is preheated by connecting it through the ballast 18 across the terminals 17 and 19. The close spacing of the anode 12 and cathode 11 results in ready starting of a glow discharge upon opening of the switch 20. The operating discharge occurs between the anode 12 and the point on the cathode 11 at which the cathode spot appears. The cathode spot always forms at the most negative point, providing it is as emissive as the rest of the cathode. The most negative point on the cathode is the turn adjacent to the lead wire 13, so that the discharge is formed across the gap B. Obviously, there is an appreciable voltage drop between the negative end of the cathode and the more positive portion opposite the anode 12. In accordance with this invention the said gap B, for the lamp specifically described herein, is greater than 2 millimeters and less than 5 millimeters, preferably 3 to 5 millimeters.

In a lamp having the specifications described above, the ballast 18 may have a resistance of about 10 ohms.

Although I have shown and described a particular species of lamp comprising my invention, it will be obvious to those skilled in the art that various modifications may be made without departing from the spirit of the invention. In order to insure that the lead 13 is connected to the negative terminal 17 of the current source upon insertion of the lamp in its socket, I prefer to use a type of base which is insertable in a socket in only one position. One such form is the well-

known bayonet pin base which is modified by spacing the pins different distances from the end of the base, as shown in Patent No. 1,788,231, J. D. Ceder, et al., dated January 6, 1931.

What I claim as new and desire to secure by Letters Patent of the United States is:

1. A gaseous electric discharge device of the low pressure cathode glow type capable of starting and operating on an approximately 12-volt circuit and comprising a sealed envelope containing an ionizable gaseous medium at a pressure of the order of a few millimeters and a stationary thermionic cathode and an anode, a pair of lead-in conductors extending into said envelope and connected to the ends of said cathode for passage of pre-heating current therethrough during starting of the device, and a third lead-in conductor connected to said anode, said cathode comprising a filamentary coil of appreciable resistance coated with electron-emissive material,

10 said anode being so located that it is spaced from the negative end of said cathode a distance greater than two millimeters but less than five millimeters but being not more than two millimeters from a portion of said cathode which is appreciably more positive than its negative end.

2. A gaseous electric discharge device of the low pressure cathode glow type capable of starting and operating on an approximately 12-volt

30 circuit and comprising a sealed envelope containing an ionizable gaseous medium at a pressure of the order of a few millimeters and a stationary thermionic cathode and an anode, a pair of lead-in conductors extending into said envelope and connected to the ends of said cathode for passage of pre-heating current therethrough during starting of the device, and a third lead-in conductor connected to said anode, said cathode comprising a filamentary coil of appreciable re-

35 sistance coated with electron-emissive material, the anode being of sheet metal form of substantial area and surrounding a portion of said cathode, said anode being so located that it is spaced from the negative end of said cathode a distance greater than two millimeters but less than five millimeters but being not more than two millimeters from a portion of said cathode which is appreciably more positive than its negative end.

3. A gaseous electric discharge device of the

40 low pressure cathode glow type capable of starting and operating on an approximately 12-volt circuit and comprising a sealed envelope containing an ionizable gaseous medium at a pressure of the order of a few millimeters and a stationary thermionic cathode and an anode, a pair of lead-in conductors extending into said envelope and connected to the ends of said cathode for passage of pre-heating current therethrough during starting of the device, and a third lead-in conductor connected to said anode, said cathode comprising a filamentary coil of appreciable re-

45 sistance coated with electron-emissive material, the anode being of sheet metal form of substantial area and surrounding a portion of said cathode, said anode being so located that it is spaced from the negative end of said cathode a distance greater than two millimeters but less than five millimeters but being not more than two millimeters from a portion of said cathode which is appreciably more positive than its negative end.

4. A gaseous electric discharge device of the low pressure cathode glow type capable of starting and operating on an approximately 12-volt circuit and comprising a sealed envelope containing an ionizable gaseous medium at a pressure of the order of a few millimeters and a stationary thermionic cathode and an anode, a pair of lead-in conductors extending into said envelope and connected to the ends of said cathode for passage of pre-heating current therethrough during starting of the device, and a third lead-in conductor connected to said anode, said cathode comprising a filamentary coil of appreciable re-

50 sistance coated with electron-emissive material, the anode being of sheet metal having a surface area of at least sixteen square millimeters and surrounding a portion of said cathode, said anode being so located that it is spaced from the negative end of said cathode a distance greater than two millimeters but less than five millimeters but being not more than two millimeters from a portion of said cathode which is appreciably more positive than its negative end.

55

5. A gaseous electric discharge device of the low pressure cathode glow type capable of starting and operating on an approximately 12-volt circuit and comprising a sealed envelope containing an ionizable gaseous medium at a pressure of the order of a few millimeters and a stationary thermionic cathode and an anode, a pair of lead-in conductors extending into said envelope and connected to the ends of said cathode for passage of pre-heating current therethrough during starting of the device, and a third lead-in conductor connected to said anode, said cathode comprising a filamentary coil of appreciable re-

60 sistance coated with electron-emissive material, the anode being of sheet metal having a surface area of at least sixteen square millimeters and surrounding a portion of said cathode, said anode being so located that it is spaced from the negative end of said cathode a distance greater than two millimeters but less than five millimeters but being not more than two millimeters from a portion of said cathode which is appreciably more positive than its negative end.
